UNITED STATES PATENT OFFICE.

HARRY W. JONES, OF SAN FRANCISCO, CALIFORNIA, ASSIGNOR TO AMERICAN CAN COMPANY, OF NEW YORK, N. Y., A CORPORATION OF NEW JERSEY.

BOX FOR CIGARETTES AND THE LIKE.

1,246,932.

Specification of Letters Patent. Patented Nov. 20, 1917.

Application filed December 18, 1915. Serial No. 67,496.

To all whom it may concern:

Be it known that I, HARRY W. JONES, a citizen of the United States, residing in San Francisco, in the county of San Francisco and State of California, have invented a new and useful Improvement in Boxes for Cigarettes and the like, of which the following is a specification.

This invention relates in general to boxes for tobacco, cigarettes and the like and has for its object broadly the provision of a box of new and improved construction for the packaging of tobacco.

A further object of the invention is the provision of such a box of cheap but rigid construction adapted to prevent crumbs and particles of tobacco from leaking out of a package which has once been opened while the same is in the pocket of the user.

A still further object of the invention is to provide such a box which, by reason of its construction, will be more or less moisture proof so that cigarettes or tobacco having been once opened may be carried in the box without appreciable danger of too rapid drying out.

A still further object of the invention is the provision of such a box having a body of fiber and ends of metal constructed and connected to provide a package which will not be readily mashed in handling or marketing and which at the same time can be made at little cost.

Another object of the invention is the provision of a relatively rigid box adapted for the packaging of cigarettes placed on end.

Other objects and advantages of the invention will be apparent as it is better understood from the following description when considered in connection with the accompanying drawing illustrating a preferred embodiment thereof.

On the drawing,

Figure 1 is a perspective view of a box embodying my invention;

Fig. 2 is a rear elevation of the same;

Fig. 3 is a side view and partial vertical section of the same;

Fig. 4 is an enlarged horizontal section taken through the hinged connection between the body and cover;

Fig. 5 is an enlarged partial rear elevation of the upper part of the body before the cover is secured thereto; and

Fig. 6 is an enlarged rear elevation of the cover before being secured in place.

For the purpose of illustrating this invention I have shown on the drawing a cigarette box consisting primarily of a body A seamed to a sheet metal bottom B and having a sheet metal hinge cover C. The body A in the present instance is of stiff paper or fibrous material oval in cross section and adapted to fit the pocket of the user. This body is seamed about its bottom edges with the flange 7 of the metal bottom B. Near its upper edge and on its rear side are provided two depressions 8 across the lower edges of which extend hinge pins or staples 9. These depressions extend from beneath the edge to points a little below said staples. The ends 10 of these pins or staples are inserted through the body A on opposite sides of the depressions and are bent back upon themselves to hold them in place. This disposes the main part 11 of each staple close against the plane of the rear face of the package. The cover C is hinged to the pins 9 and to this end it is provided with a pair of hinge lips 12 extending downwardly from a peripheral flange 13 disposed about the closure to engage the sides of the box. These lips are bent to the U-shape form shown in Fig. 3 and their inner ends are inserted upwardly behind the pins 11, after which they may be mashed back to prevent disconnection of the cover and body. The flange 13 is of less depth in back than in front in order that the cover when positioned may be readily closed about the package. When thus constructed the free edge will clear the upper edge of the front wall of the body and not tear the body or tend to strip a label 14 therefrom as the cover closes, the hinge pins 9 being located substantially on a level with the middle of the front part of the cover flange 13.

A package of this character may be rendered moisture proof by any suitable proofing. The construction of the top and bottom of metal results not only in the formation of easily applied ends to the package but results also in greatly strengthening the box and enabling it to resist crushing strains in transit and in handling by the dealer.

It is thought that the invention and many of its attendant advantages will be understood from the foregoing description, and it will be apparent that various changes may

be made in the form, construction and arrangement of the parts without departing from the spirit and scope of the invention or sacrificing any of its material advantages, the form hereinbefore described being merely a preferred embodiment thereof.

I claim:

1. A tobacco box comprising an oval flat-tened body of fibrous material, the rear wall of said body being depressed inwardly at points adjacent its open end; staples inserted through the rear wall of the body, extending across said depressions and having their ends clamped upon the interior of said rear wall; and a hinged sheet metal closure which is peripherally flanged, having its rear flange cut to form downwardly extending bendable lips which are formed into U-shape and inserted in said depressions of the rear wall at the under and inner sides of said staples.
2. A tobacco box comprising an oval flat-

tened body of fibrous material, the rear wall of said body being depressed inwardly at points adjacent its open end; staples inserted through the rear wall of the body, extending across said depressions and having their ends clamped upon the interior of said rear wall; and a hinged sheet metal closure which is peripherally flanged, having its rear flange cut to form downwardly extending bendable lips which are formed into U-shape and inserted in said depressions of the rear wall at the under and inner sides of said staples, and having its front flange extended substantially equally both above and below the level of said staples.

Signed in the presence of two subscribing witnesses.

HARRY W. JONES.
